DRY, FREE-FLOWING MEAT CURING
COMPOSITIONS

William Delaney, Chicago, Ill., assignor to Kadison Laboratories, Inc., Chicago, Ill., a corporation of Delaware
No Drawing. Filed Apr. 7, 1961, Ser. No. 101,358
13 Claims. (Cl. 99—222)

My invention relates to certain new and useful meat curing compositions in the form of dry, free-flowing products.

Conventional meat curing compositions contain alkali metal nitrites and/or nitrates, notably sodium nitrite and/or sodium nitrate, usually in admixture with one or more other materials such as common salt; cane sugar; corn sugar or dextrose; ascorbic acid and isomers of ascorbic acid such as L-ascorbic acid, D-ascorbic acid and D-isoascorbic acid and water-soluble salts thereof, most commonly the alkali metal salts; as well as other materials. In the dry form, as distinguished from aqueous solutions thereof, it has long been known that such compositions are unstable and deteriorate in shipment and in storage. Thus, for instance, a variety of reactions takes place in the dry compositions as, for example, conversion of nitrate to nitrite and liberation of nitrogen oxides from the nitrite, and not infrequently undesirable discoloration of the dry curing composition occurs.

Various efforts have been made effectively to solve this problem. Thus, for instance, in dry meat curing compositions which comprise essentially sodium chloride, alkali metal nitrite with or without alkali metal nitrate, and an alkali metal salt of ascorbic acid or an isomer of ascorbic acid, it has been proposed, and commercially practiced, to incorporate into said dry compositions an alkaline material such as sodium carbonate within controlled limits to stabilize the dry compositions against loss of nitrite in storage and shipment. Such procedures leave much to be desired from a number of standpoints including their relative effectiveness.

It has been found, in accordance with the present invention, that dry or solid, free-flowing meat curing compositions can be prepared which remain stable and free from deterioration on storage or shipment over prolonged periods of time in a simple fashion. This is achieved by coating the pulverulent particles or crystals of the alkali metal nitrite and/or nitrate with a non-hygroscopic film or thin coating of an innocuous material. In those meat curing compositions which contain both an alkali metal nitrite and an alkali metal nitrate, it is particularly preferred to coat the particles or crystals thereof with an essentially continuous film or coating of the non-hygroscopic coating material but, in any event, the alkali metal nitrite should be coated since it is most susceptible to breakdown or deterioration. Similarly, where the meat curing compositions contain alkali metal nitrite and/or nitrate and ascorbic acid or its isomers, or the innocuous salts thereof, non-hygroscopic innocuous essentially continuous coatings can be provided on the particles or crystals thereof but, again, for best results, the alkali metal nitrite particles or crystals at least should be provided with such a coating.

The non-hygroscopic coatings which are available for use may be selected from a large group of materials which are solid at room temperatures and preferably up to 110 or 120 degrees F., illustrative examples of which are solid fats such as tallow; hydrogenated oils such as corn oil, cottonseed oil and soya bean oil; mono- and di-glycerides and polyglycerides of normally solid higher fatty acids such as palmitic acid and stearic acid; lecithins; higher fatty acids such as palmitic acid and stearic acid as such or in admixture with lesser quantities of polyhydroxy compounds such as glycerol, propylene glycol and

2

sorbitol; carboxymethyl celluloses; methylcellulose; ethylcellulose; starches; and the like. I find it particularly desirable for the purposes of the present invention to use, as coating materials, those which are water-soluble or readily water-dispersible, particularly at room temperatures or below, especially satisfactory being higher fatty acid monoglycerides and diglycerides or mixtures thereof, higher fatty acid polyglycerides, higher fatty acid partial esters of sorbitol and sorbitan, higher fatty acid partial esters of sugars and of methyl glucosides, and, in general, higher fatty acid partial esters of aliphatic water-soluble polyhydric alcohols or polyhydroxy substances; and water-soluble gum-like compounds such as sodium carboxymethyl celluloses.

The manner in which the particles or crystals of the alkali metal nitrites and nitrates and the ascorbic acids or ascorbates are coated with an essentially continuous film or coating of the non-hygroscopic innocuous coating material forms no part of my present invention. This can readily be accomplished in a variety of ways which, from a coating technique standpoint per se, are well known in the art. Thus, for instance, if the coating material is meltable at sufficiently low temperature so that, at such temperature no untoward reactions occur with the alkali metal nitrite crystals or other pulverulent particles to be coated, it may be admixed in pulverulent form with the alkali metal nitrite crystals or other pulverulent particles, then sieved a plurality of times through an 80 to 100 mesh screen, then heated to just above the melting point of the coating material and rapidly and intimately stirred continuously while allowing the mass to cool and dry. Another procedure is to dissolve the coating material in a volatile organic solvent, spray the coating solution on the crystals of sodium nitrite or other pulverulent material while agitating the same, and then to evaporate off the organic solvent. The particular techniques of effecting the coating are not material to my present invention so long as they provide an essentially continuous thin film or coating on the alkali metal nitrite crystals or other pulverulent material to be coated, and the final solid meat curing compositions which embody the coated ingredients are free-flowing.

The following examples are illustrative of solid, free-flowing meat curing compositions falling within the scope of the invention. It will be understood that other compositions can readily be evolved following the guiding principles and teachings provided herein. The numerical values represent parts by weight.

Example 1

50	Sodium chloride	90
	Sodium nitrate	5
	Sodium nitrite	4
	Sodium ascorbate	1

55 The sodium nitrate and sodium nitrite crystals are coated with a film of tallow fatty acid monoglycerides.

Example 2

60	Sodium chloride	200
	Cane sugar	35
	Sodium nitrate	1.5
	Sodium nitrite	2
	Sodium D-isoascorbate	4

65 The sodium nitrate and sodium nitrite crystals are coated with a film of sodium carboxymethyl cellulose.

Example 3

70	Cane sugar	100
	Potassium nitrate	8
	Potassium nitrite	10
	Sodium ascorbate	20

The potassium nitrite and sodium ascorbate crystals are coated with a film of sorbitan mono-stearate.

Example 4

Sodium chloride	100
Sodium nitrite	5
Sodium ascorbate	12

The sodium nitrite crystals are coated with a film of sodium carboxymethyl cellulose.

Example 5

Sodium chloride	105
Sodium nitrite	11
Sodium nitrite	16
Dextrose	15

The sodium nitrate and sodium nitrite crystals are coated with a film of ethylcellulose.

Example 6

Sodium chloride	1125
Sodium nitrite	125
Dextrose	10

The sodium nitrite crystals are coated with a film of sodium carboxymethyl cellulose.

Example 7

Sodium chloride	190
Cane sugar	125
Sodium nitrite	1
Sodium nitrate	8
Ascorbic acid	1

The sodium nitrite, sodium nitrate and ascorbic acid crystals are coated with a film of triple pressed stearic acid monoglyceride.

While particular embodiments of the invention have been described in order to illustrate the invention, it will be obvious to those skilled in the art that various changes and modifications may be made, in the light of the guiding principles and teachings provided herein, without departing from the invention in its broader aspects and, therefore, the appended claims are intended to encompass all such changes and modifications as fall within the spirit and scope of the invention.

What I claim as new and desire to protect by Letters Patent of the United States is:

1. A solid, free-flowing meat curing composition which includes at least one compound in pulverulent form selected from the group consisting of alkali metal nitrites and nitrates, said pulverulent compound being coated with a non-hygroscopic innocuous protective coating.

2. A solid, free-flowing meat curing composition which includes a pulverulent alkali metal nitrite the particles of which are coated with a non-hygroscopic water-soluble innocuous protective coating.

3. A solid, free-flowing meat curing composition which includes pulverulent sodium nitrite the particles of which are coated with a film of sodium carboxymethyl cellulose.

4. A solid, free-flowing meat curing composition which

includes pulverulent sodium nitrite the particles of which are coated with a film of a higher fatty acid partial ester of a water-soluble aliphatic polyhydroxy compound.

5. A solid, free-flowing meat curing composition which includes pulverulent sodium nitrite the particles of which are coated with a film of a member selected from the group consisting of monoglycerides, diglycerides and mixtures thereof.

6. A solid, free-flowing pulverulent meat curing composition which includes (a) a member selected from the group consisting of ascorbic acid and its isomers and their water-soluble salts, and (b) an alkali metal nitrite, at least one of said (a) and (b) ingredients being coated with a non-hygroscopic innocuous protective coating.

7. A solid, free-flowing pulverulent meat curing composition which includes an alkali metal ascorbate and an alkali metal nitrite, said alkali metal nitrite being coated with a non-hygroscopic innocuous protective coating.

8. A solid, free-flowing pulverulent meat curing composition which includes sodium ascorbate and sodium nitrite, the sodium nitrite being coated with a non-hygroscopic innocuous protective coating.

9. A solid, free-flowing pulverulent meat curing composition which includes sodium isoascorbate and sodium nitrite, at least one of said ingredients being coated with a non-hygroscopic water-soluble innocuous protective coating.

10. A solid, free-flowing pulverulent meat curing composition which includes sodium ascorbate and sodium nitrite, at least one of said ingredients being coated with a non-hygroscopic water-soluble innocuous protective coating.

11. A solid, free-flowing pulverulent meat curing composition which includes (a) a member selected from the group consisting of ascorbic acid and its isomers and their water-soluble salts, and (b) an alkali metal nitrite, said alkali metal nitrite being coated with a film of sodium carboxymethyl cellulose.

12. A solid, free-flowing pulverulent meat curing composition which includes (a) a member selected from the group consisting of ascorbic acid and its isomers and their water-soluble salts, and (b) an alkali metal nitrite, said alkali metal nitrite being coated with a film of a higher fatty acid partial ester of a water-soluble aliphatic polyhydroxy compound.

13. A solid, free-flowing pulverulent meat curing composition which includes (a) a member selected from the group consisting of ascorbic acid and its isomers and their water-soluble salts, and (b) an alkali metal nitrite, said alkali metal nitrite being coated with a film of a member selected from the group consisting of monoglycerides, diglycerides and mixtures thereof.
